THERMALLY ACTUATED FREQUENCY
CONTROLEdwin T. Jaynes, Garden City, N. Y., assignor to
The Sperry Corporation, a corporation of Dela-
ware

Application January 24, 1944, Serial No. 519,585

17 Claims. (Cl. 315—5)

1

This invention relates to frequency control and is particularly concerned with electrical or thermally sensitive frequency control arrangements for hollow resonator apparatus.

In a thermally responsive hollow resonator frequency control system wherein expansible and contractible struts or wires are electrically heated, it is desirable to maintain the system substantially at or near a selected normal operating frequency approximately at the middle of the range of frequency control. In prior systems within my knowledge, this has usually been accomplished by maintaining a strut or wire constantly energized so as to provide a condition of substantially dynamic balance in the system at the selected resonator frequency. The chief objections to these prior systems are that they continually use power, and that the adjustment of the circuits is lost when the receiver or other apparatus using the system is turned off.

It is a major object of the invention to provide a novel electrically energized frequency control system for hollow resonator apparatus having arrangements whereby the resonator frequency may be independently preset at a desired operating point within a preselected control range without electrical energization of the system.

A further object of the invention is to provide a hollow resonator frequency control system embodying independently acting thermally responsive frequency control members for varying the resonator frequency in opposite directions and novel associated arrangements for adjusting the resonator frequency independently of energization of said thermal responsive members.

A further object of the invention is to provide a novel assembly of electrically and manually operable frequency controls for hollow resonator apparatus.

It is a further object of the invention to provide novel arrangements for automatically controlling the operating frequency of hollow resonator apparatus.

Further objects of the invention will presently appear as the description proceeds in connection with the appended claims and the annexed drawings wherein:

Figure 1 is an elevation partly in section of a velocity modulation hollow resonator device embodying frequency control arrangements according to the invention;

Figure 2 is a diagrammatic representation of an automatic frequency control system wherein the device of Figure 1 may be used; and

Figure 3 is a wiring diagram illustrating fur-

2

ther details of part of the automatic frequency control system of Figure 2.

Referring first to Figure 1, the illustrated hollow resonator device comprises a pronged base 11 of the usual vacuum tube type and a cathode surrounding structure consisting of a glass collar 12 sealed to base 11 and a metal collar 13 sealed to collar 12.

At its upper end, collar 13 is formed with a reduced coaxial hollow tubular extension 14 which is secured to a cylindrical hollow conductive resonator body 15. Collar 13 and resonator body 15 have secured thereto parallel spaced radial flanges 16 and 17, respectively, which extend normal to the resonator axis. Above flange 17, a metal collar 18 is secured to resonator 15, and the upper end of collar 18 is sealed and closed by a glass end cap 19.

Base 11, collars 12 and 13, tube 14, resonator 15, collar 18 and cap 19 constitute a vacuum sealed envelope, and the cathode (not shown) projects a stream of electrons along the resonator axis through resonator 15. A reflector electrode 21 mounted on a conductor 22 sealed in cap 19 and fixed to external terminal 23 is centered with the resonator axis.

As illustrated in section in Figure 1, the upper end of tube 14 is fixed to a flexible end wall 24 of resonator 15 and extends through wall 24 to provide a reentrant hollow pole 25 within resonator 15. Parallel apertured grids 26 and 27 are mounted in adjacent spaced relation upon the upper end of pole 25 and in a suitable central aperture in the relatively stiff upper end wall 28 of resonator 15 which is rigid with flange 17. Thus, grids 26 and 27 are rigid with flanges 16 and 17 respectively and are effectively flexibly interconnected by wall 24.

Flanges 16 and 17 are interconnected by a tension spring 29. A pair of rigid parallel struts 31 having their opposite ends reduced for interfitting with suitable locating recesses on flanges 16 and 17 are interposed between flanges 16 and 17.

Only one strut 31 is illustrated in Figure 1 since the other strut is directly behind that shown and equidistant from spring 29. Since struts 31 are disposed on the same side of the center line of the device as spring 29, it is clear that flanges 16 and 17 are fulcrumed about the strut ends and that spring 29 tends to rock flanges 16 and 17 about parallel lateral axes substantially perpendicular to the resonator axis in such manner as to increase the resonator grid gap. This tendency of spring 29 to separate grids 26 and 27 is opposed

and controlled by the structure at the right side of Figure 1.

Flange 16 has secured thereto, as by bolt 32, a bracket 33 upon which is rigidly mounted a hollow tube 34. The lower end of tube 34 is closed by a plug 35 which is centrally tapped to receive an adjustable threaded element 36. A suitable locknut 37 locates element 36 in any position of axial displacement.

A rigid support member 38 which freely extends radially into tube 34 through a suitable aperture 39 is fixed to flange 17, as by bolt 40. A suitable closure 41 is provided for the top end of tube 34. Diametrically opposite aperture 39, tube 34 is provided with an aperture 42 which is formed with a knife edge portion 43 serving as a fulcrum for one arm of a bifurcated lever 44 extending through aperture 42. The other arm of lever 42 is engaged by an adjustable threaded member 45 mounted on an upstanding part of bracket 33.

A rigid body 46 of glass or like insulating material is provided with spaced imbedded stiff conductor rods 47 and 47', and the oppositely projecting ends of rods 47 and 47' are secured as by soldering or welding to the lower ends of flexible conductor wires or strips 48 and 49 respectively which have their upper ends anchored respectively to support 38 and lever 44 as illustrated. A tension spring 51 is interposed between body 46 and adjustable element 36, so as to maintain both conductors 48 and 49 taut and to oppose spring 29.

Conductors 48 and 49 have their lower ends electrically connected to external leads 52 and 53 respectively extending through suitable insulated bushings on tube 34. The upper ends of conductors 48 and 49 are grounded to the resonator frame, and leads 52 and 53 are connected to suitable separate energy sources for selectively independently passing and/or varying heating current through conductors 48 and 49 as will be described below in an important example.

In operation, the electron stream from the cathode initially traverses the gap between resonator grids 26 and 27 and is then returned by reflector 21 into resonator 15, so as to excite and maintain an oscillatory electromagnetic field in resonator 15. Accepted theories of this action based on electron velocity modulation principles are explained fully in United States Letters Patent No. 2,250,511 to which reference is made for further details. Microwave energy is extracted from the resonator field as by the usual concentric line terminal assembly 52.

It is known that changes in volume and shape of resonator 15, such for example as may be occasioned by changes in the spacing of grids 26 and 27, result in corresponding variations in resonator frequency. This property is utilized in the present invention.

Manual control of the resonator frequency is obtainable by adjustment of member 45. When member 45 is turned to cause clockwise rotation of lever 44, this motion is transmitted through conductor 49 to displace body 46 upwardly against the tension of spring 51. The resulting slackness of conductor 48 is promptly taken up by the action of spring 29 in relatively rocking flanges 16 and 17. Where the device is seated in a stationary socket for example, under these conditions spring 29 will cause flange 17 to rock counterclockwise about its fulcrum thereby increasing the gap between grids 26 and 27 and increasing the resonator frequency.

Conversely, when member 45 is turned in the opposite direction, lever 44 is free to rock counter-

clockwise under the pull of spring 51 so that body 46 is displaced downwardly, thereby relatively rocking flanges 16, 17. Again where the device is seated in a stationary socket, the downward motion of body 46 transmitted by conductor 48 causes flange 17 to rock clockwise about its fulcrum against the opposition of spring 29. Spring 51 is therefore selected of sufficient strength relative to spring 29 and the leverage of the associated parts to accomplish this operation.

The tension of spring 51 is preset by adjustment of element 36, and this maintains the parts in a tight assembly very sensitive to control forces. In practice, the tension of spring 51 is about twice that of conductor 48 because of the pull of spring 29.

Assume that conductor 49 is heated hotter than conductor 48, as by passage of electric current therealong. Conductor 49 is elongated more than conductor 48, thereby permitting spring 51 to downwardly displace body 46, conductor 48, flange 17 and grid 27 to decrease the frequency of resonator 15. Reversely, when conductor 48 is heated more than conductor 49, conductor 48 elongates more than conductor 49, thereby permitting spring 29 to effect upward displacement of grid 27 and consequent increase in the frequency of resonator 15.

Under practical operating conditions, it is possible to first adjust the resonator frequency to a predetermined operating point by the manual control at 45, and then speedily effect desired variations in the resonator frequency in opposite directions from that operating point by suitable energization of conductors 48 and/or 49.

The above described device is especially useful in an automatic frequency control system such as illustrated in Figures 2 and 3 and described below.

Figure 2 illustrates a representative system 40 wherein the invention is usable and wherein the output frequency of a local oscillator source 54 is automatically controlled to maintain a desired intermediate frequency. Source 54 may be the device of Figure 1, and source 55 may be any 45 similar device or high frequency wave receiver. The outputs of sources 54 and 55 are combined in mixer 56, and the intermediate frequency output of mixer 56 is amplified at 57 and introduced into a discriminator 58. Signals from discriminator 58 are fed into a frequency control circuit 59 which in turn is connected to energize suitable frequency control elements in source 54, such as conductors 48 and 49.

Figure 3 illustrates a detailed circuit arrangement 55 usable for carrying out this phase of the invention.

Discriminator transformer primary 61 is connected across the output of intermediate frequency amplifier 57 in parallel with variable condenser 62 by which the primary transformer circuit may be tuned to the desired intermediate frequency. A reference voltage from primary 61 is applied through phase shifting condenser 60 to the midpoint of transformer secondary 63.

Discriminator transformer secondary 63 is connected in parallel with a variable condenser 64, by which the secondary transformer circuit may also be tuned to the desired intermediate frequency. Opposite ends of secondary 63 are connected to the anodes of diode rectifiers 65 and 66, and the cathodes of rectifiers 65 and 66 are connected to an impedance 67 through equal resistors 68 and 69, respectively, and to ground through equal output resistors 70 and 71. Alter-

nating current bypass condensers 72 and 72' are provided across resistors 68 and 69 respectively, and the center of transformer secondary 63 is connected to the other side of impedance 67.

The output of discriminator 58 controls the frequency control circuit which comprises substantially the remainder of Figure 3 except conductors 48 and 49.

Alternating voltage for the control circuit is derived from a source 73, which is connected through condensers 74 and 75 to the control grids 76, 77 of variable-mu pentodes 78 and 79 respectively. The output of discriminator 58 is likewise connected to grids 76, 77 through resistors 81 and 82 which impede flow of alternating current to the discriminator. Condensers 74 and 75 block against flow of direct current to source 73.

The cathodes of pentodes 78, 79 are interconnected by a resistor 83 connected through adjustable taps 84 and 85 to grounded resistor 86. Adjustment of tap 84 varies the relative bias of pentodes 78 and 79, while adjustment of tap 85 varies the bias of these tubes concomitantly. The purpose of these adjustments will appear later.

The screen grids of pentodes 78, 79 are connected together and through screen dropping resistor 87 to a suitable high voltage plate circuit supply indicated at 88. A voltage regulator tube 89 is provided to prevent the screen voltage of tubes 78 and 79 from varying with control grid bias, and to avoid degeneration due to alternating current on the screen grids.

The anodes of pentodes 78 and 79 are connected through respective load resistors 91 and 92 to plate supply 88. Coupling condensers 93, 94 connect resistors 91, 92 to input resistors 95, 96 respectively of a power amplifier stage including conventional tetrodes 97 and 98. The common junction of input resistors 95, 96 is connected through grid biasing battery 99 to the cathodes of tetrodes 97, 98.

Input resistors 95, 96 are connected to control grids 101, 102 of tetrodes 97, 98. The anodes of tetrodes 97, 98 are connected through output transformer primaries 103, 104 to a common screen grid lead which in turn is connected to a high voltage plate supply 105 for the power amplifier stage. Conductors 48 and 49, which are resistances electrically, are connected across output transformer secondaries 106, 107 for receiving energy from opposite sides of the amplifier stage.

In operation of the circuit of Figure 3, the currents in discriminator output resistors 67, 68 provide unidirectional voltage drops which are applied to control grids 76 and 77 respectively, thus varying the relative bias of the pentodes 78 and 79. Operation of this type of discriminator is well known, the relative values of the voltage drops across resistors 68 and 69 depending upon the direction and degree of departure from the desired intermediate frequency. Source 73 superposes an equal alternating voltage on each of control grids 76 and 77.

When the output frequency of amplifier 57 is that for which discriminator 58 is tuned, the currents in resistors 68, 69 are equal and opposite, thereby applying no voltage to grids 76 and 77. Under such conditions pentodes 78 and 79 are equally conductive, provided tap 84 is correctly adjusted; and the gain of tubes 78 and 79 may be varied by means of tap 85. In particular these tubes may be made to have very low gain.

Under these conditions the signals applied to grids 101 and 102 of tetrodes 97 and 98 are equal and may be made very small if desired. Hence conductors 48 and 49 are equally energized and there is no tendency for the frequency of the device in Fig. 1 to change.

However, suppose that the intermediate frequency departs in a direction such that the current through resistor 68 is larger than the current through resistor 69. The action of resistance network 68, 69, 70, 71, 81, 82 is then to decrease the bias on pentode 78 and increase the bias on pentode 79. Due to the well-known action of variable-mu tubes, this increases the gain of pentode 78 and decreases the gain of pentode 79. Conductor 48 is then heated more than conductor 49. Referring back to the operation of Figure 1, the above described increased heating of conductor 48 produces an increase in the frequency of resonator 15.

When the output frequency of amplified 57 departs in the opposite direction, this results in increase in the gain of pentode 79 and decrease in the gain of pentode 78 and conductor 49 is now heated more than conductor 48, so as to cause reduction in the frequency of resonator 15.

Adjustment of tap 85 simultaneously controls the amplitude of the heating current deliverable to both conductors 48 and 49, and this adjustment is made in different ways depending on what characteristics one desires of the system. If low power consumption is important, tap 85 should be set so that the gain of pentodes 78 and 79 is very low when the intermediate frequency at 57 is at the correct value. Practically no power is then delivered to either of conductors 48 and 49. Power will be delivered to conductors 48 and 49 only to correct frequency deviations, and only one conductor at a time will be heated. If, on the other hand, one desires the greatest possible speed of response of the automatic frequency control system, a further factor of almost two can be obtained by setting tap 85 so that the voltage gain of the pentodes is sufficient to result in power being fed to conductors 48 and 49 continuously, so that any frequency deviations will cause one conductor to expand and the other to contract an equal amount, thus substantially multiplying the effect which would be obtained by having only one conductor at a time respond.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. High frequency apparatus comprising a hollow resonator having relatively movable means for varying the frequency of said resonator, separately acting thermally sensitive longitudinally expansible means operably connected to said relatively movable means, the longitudinal expansion of said expansible means moving said movable means to selectively independently vary the resonator frequency in opposite directions, one of said expansible means having an end connected mechanically to one of said movable means, the other of said expansible means having an end connected mechanically to the other of said movable means, the other ends of each of said expansible means being connected to an insulating 75 mounting means and manually adjustable means

in said apparatus operably connected to said movable means for selectively independently varying the resonator frequency regardless of energization of said thermally sensitive means.

2. The apparatus defined in claim 1, wherein said thermally sensitive longitudinally expansible means comprises two separately energizable electrical conductors operably connected to said movable means.

3. High frequency apparatus comprising a hollow resonator having two parts which are relatively movable for varying the frequency of said resonator, independently actuatable separately acting axially expansible and contractible means, one having an end connected mechanically to one of said parts, the other having an end connected mechanically to the other of said parts, the other ends of each of said means being connected to an insulating mounting means for selectively varying the resonator frequency in opposite directions relative to a predetermined reference point, and means in said apparatus for selectively independently varying the resonator frequency for shifting said reference point.

4. High frequency apparatus comprising a hollow resonator having wall portions which are relatively movable for varying the frequency of said resonator, a pair of thermally sensitive members operably connected to said wall portions and selectively relatively energizable for independently varying the resonator frequency in opposite directions, one of said members having an end connected mechanically to one of said portions, the other of said members having an end connected mechanically to the other of said portions, the other ends of each of said members being connected to an insulating mounting means, and manually operable means including an adjustable lever in said apparatus operably connected to said hollow resonator for varying the resonator frequency independently of the energization of said members.

5. High frequency apparatus comprising a hollow resonator device having parts which are relatively movable for varying the frequency of said resonator, separate longitudinally expansible and contractible frequency control members, one of said members having an end connected mechanically to one of said parts, the other of said members having an end connected to the other of said parts, the other ends of each of said members being connected to an insulating mounting means, said members being selectively actuatable for relatively moving said parts in a direction substantially parallel to the expansion and contraction of said means and independently varying the resonator frequency in opposite directions, and further frequency control means also operably connected to said parts for varying the resonator frequency independently of said actuation of said separate frequency control means.

6. The apparatus defined in claim 5, wherein said separate frequency control means constitute portions of said further frequency control means.

7. High frequency apparatus comprising a hollow resonator device having parts which are relatively movable for varying the frequency of said resonator, separate thermally sensitive longitudinally expansible and contractible members, one of said members having an end connected mechanically to one of said parts, the other of said members having an end connected to the other of said parts, the other ends of each of said members being connected to an insulating mounting means, said members being operably con-

nected to said parts and selectively energizable by the passage of electric current therethrough for independently varying the frequency of said resonator in opposite directions, and means in said apparatus for varying said resonator frequency independently of energization of said members.

8. The apparatus defined in claim 7, wherein said last named means comprises motion transmitting mechanism including said thermally sensitive members.

9. High frequency apparatus comprising a hollow resonator having a pair of wall portions which are relatively movable for varying the frequency of said resonator, laterally extending members rigid with said respective wall portions, a mounting body resiliently connected to one of said members, a pair of thermally sensitive electrical conductors having corresponding ends anchored in spaced relation on said body so as to be electrically insulated from each other at said ends, means fixing the other end of one of said conductors to one of said members, and adjustable lever means between the other end of said other conductor and the other of said members.

10. The apparatus defined in claim 9, wherein said mounting body comprises a body of insulating material.

11. High frequency apparatus comprising a tunable hollow resonator device having relatively movable wall portions, a first thermally sensitive member operably connected to said device and energizable for varying the resonator frequency in one direction, one end of said first member being connected mechanically to one of said portions a second thermally sensitive member operably connected to said device and energizable for varying the resonator frequency in the opposite direction, one end of said second member being connected mechanically to the other of said wall portion, the other ends of both of said first and second members being connected to an insulating mounting means, and manually operable means embodying motion transmitting mechanism containing said thermally sensitive members for varying the resonator frequency independently of the degree of energization of said thermally sensitive members.

12. High frequency apparatus comprising a hollow resonator device having two parts which are relatively movable for varying the frequency of said resonator, two flexible thermally responsive members in said apparatus each having one end connected to a respective one of said parts, means for mounting the other ends of said members in electrically insulated relation, and manually operable means for adjusting said mounting means in opposite directions for independently varying said resonator frequency.

13. The apparatus defined in claim 12, wherein said adjusting means comprises means resiliently connecting said mounting means to one of said parts and an adjustable rockable lever interposed between one of said members and one of said parts.

14. An electron discharge device comprising a hollow resonator having relatively movable electron permeable wall portions mounted in alignment to permit passage of an electron stream through the resonator field in the gap between said portions, a mounting member resiliently connected to one of said wall portions, two thermally sensitive expansible and contractible flexible conductors having corresponding ends secured in electrically insulated relation to said mounting

member, means securing the other ends of said flexible conductors to said respective wall portions, lateral flanges rigid with said respective wall portions, and means mounting said flexible conductors and securing means on said flanges.

15. Electron discharge apparatus comprising means for producing a stream of electrons, an adjustable hollow resonator having relatively movable portions and positioned along the path of said stream in energy-exchanging relation therewith, an envelope providing a vacuum-tight enclosure for said stream, a pair of thermally sensitive expansible and contractible conductors carried on said envelope exteriorly thereof, each of said conductors having one end thereof connected to a respective one of said movable portions, adjustable means mounting the other ends of said conductors in electrically insulated relation, and means coupled to said conductors and providing for electrical energization thereof, whereby said resonator is adjustable in opposite directions in accordance with alterations in length of said conductors produced by said electrical energization.

16. The electron discharge apparatus defined in claim 15 further having manually operable means connected at one end of one of said conductors for adjusting said resonator independently of the energization of said pair of conductors.

17. High frequency apparatus comprising a hollow resonator having relatively movable portions, two thermally sensitive extensible and contractible members, one of said members having an end connected mechanically to one of said portions, the other of said members having an end connected to the other of said portions, the

other ends of each of said members being connected to an insulating mounting body, means for varying the temperature of said thermally sensitive means to produce variations in the length thereof and corresponding variations in the resonant frequency of said resonator, and manually operable means, including motion transmitting means embodying said thermally sensitive means, for adjusting the relative spacing between said relatively movable means whereby variations in the resonant frequency of said resonator may be produced independently of said thermally sensitive means.
